[57] CLAIM

The ornamental design of an edible product, as shown and described.

DESCRIPTION

FIG. 1 is a top perspective view of the edible product showing the new design;

FIG. 2 is a front elevational view thereof;

FIG. 3 is a top plan view thereof, the bottom being a mirror image of same;

FIG. 4 is a side elevational view thereof;

FIG. 5 is a rear elevational view thereof;

FIG. 6 is a top perspective view of a second embodiment thereof, it being understood that the side, rear and bottom views are the same as in the first embodiment;

FIG. 7 is a front elevational view thereof;

FIG. 8 is a top perspective view of a third embodiment thereof, it being understood that the side, rear and bottom views are basically the same as in the first embodiment; and,

FIG. 9 is a front elevational view thereof.
